(57) **CLAIM**

The ornamental design for a pulse oximeter stand, as shown and described.

DESCRIPTION

FIG. 1 is a front perspective view of a pulse oximeter stand showing our new design, with a pulse oximeter disposed in the stand;

FIG. 2 is a front elevational view thereof;

FIG. 3 is a rear elevational view thereof;

FIG. 4 is a left side elevational view thereof;

FIG. 5 is a right side elevational view thereof;

FIG. 6 is top plan view thereof;

FIG. 7 is a bottom plan view thereof; and,

FIG. 8 is a rear perspective view thereof.

The broken line showing of a pulse oximeter device represents environmental subjected matter and forms no part of the claimed design. All other broken lines are included for the purpose of illustrating portions of the pulse oximeter stand that form no part of the claimed design.
